[57] CLAIM

The ornamental design for a cooler chest, as shown and
described.

DESCRIPTION

FIG. 1 is a front, left side, top perspective view of the cooler
chest showing the design thereof and in which a zipper pull
used is shown in broken line, this broken line element is for
illustrative purposes only and forms no part of the claimed
design;

FIG. 2 is a front elevational view thereof;

FIG. 3 is a rear side elevational view thereof;

FIG. 4 is a left side elevational view thereof, a right side
elevational view is not provided as it is a mirror image of the
left side elevational view;

FIG. 5 is a top plan view thereof; and,

FIG. 6 is a bottom plan view thereof.
